(57) **CLAIM**

The ornamental design for a fade duster as shown and described.

DESCRIPTION

FIG. 1 is a perspective view of a fade duster showing our new design.

FIG. 2 is another perspective view thereof.

FIG. 3 is a rear view thereof.

FIG. 4 is a front view thereof.

FIG. 5 is a right side view thereof.

FIG. 6 is a left side view thereof.

FIG. 7 is a top view thereof; and,

FIG. 8 is a bottom view thereof.

The claimed fade duster is used by barbers and hair stylists, and others. The end with the short bristles is used to clear out cut short hairs when doing precise haircuts with hair clippers and to line up uncut hair precisely. The end with long bristles is used to clear the cut hair from the neck, shoulders, and other surfaces as needed.

The broken lines shown in the drawings do not form part of the claimed design.
